M. C. LYDDANE

HANDLE ATTACHING MEANS FOR DOOR LATCHES

Filed July 28, 1926

UNITED STATES PATENT OFFICE.

MORTIMER C. LYDDANE, OF YONKERS, NEW YORK, ASSIGNOR TO LEON OTTINGER, OF NEW YORK, N. Y.

HANDLE-ATTACHING MEANS FOR DOOR LATCHES.

Application filed July 28, 1926. Serial No. 125,342.

This invention relates to handle attaching means for door latches, and more particularly to means for effecting a rigid connection between the handle shaft and the operating rollback of latches of that type generally used on automobile doors.

It is the primary object and purpose of the present improvements to provide a means whereby the latch handle shaft as 10 it is inserted into the bore of the rollback, will automatically be rigidly locked against either rotative or axial movement relative to the rollback so that said shaft and the rollback in effect will operate as a one piece 15 unit.

The present invention is more or less closely identified with devices of the general construction shown and described in a co-pending application for patent filed by 20 Leon Ottinger, Serial No. 122,762, on July 16, 1926, wherein the end of the handle shaft is longitudinally split and is adapted to be expanded within the rollback bore. It is one of the prominent features of the invention to provide a relatively simple means arranged in fixed relation to the inner end of the rollback and with which suitably formed means on the extremity of said split end of the handle shaft is adapted to coact to there- 25 by automatically spread or expand said shaft end as it is inserted into the rollback bore and effect a tight frictional binding engagement of the shaft parts against the opposite walls of said bore.

The invention further contemplates the provision of expanding means for the shaft end of novel form and simple construction which may be readily associated or assembled in connection with the end of the rollback without necessitating any radical structural changes in the latter, from the usual form of rollback used in such latches, and in one embodiment of my invention, I provide a shaft expanding means which 45 may be readily disconnected or detached from the rollback when it is necessary to remove the handle shaft, and without first detaching or removing the upholstery upon the inner side of the door.

It is also an additional object of my invention to provide such means for automatically locking the shaft end in connection with the rollback which is so constructed and arranged, that the shaft end will not

project from the inner end of the rollback 55 beyond the plane of the inner face of the door.

With the above and other objects in view, the invention consists in the improved handle attaching means for door latches and 60 in the form, construction and relative arrangement of its several parts as will be hereinafter more fully described, illustrated in the accompanying drawings, and subsequently incorporated in the subjoined 65 claims.

In the drawings, wherein I have shown several simple and practical embodiments of the invention, and in which similar reference characters designate corresponding 70 parts throughout the several views,—

Figure 1 is a horizontal section of a portion of an automobile door illustrating one embodiment of the present invention;

Fig. 2 is an enlarged detail horizontal 75 section showing the split end of the handle shaft inserted in the rollback bore prior to the expansion of said shaft;

Fig. 3 is a similar view showing the split end of the shaft expanded and locked in 80 connection with the rollback;

Fig. 4 is an enlarged end elevation, a conventional means being shown in dotted lines for the purpose of detaching the shaft expanding means from the rollback; 85

Fig. 5 is a horizontal section similar to Fig. 3 showing a modified form of the device;

Fig. 6 is an end elevation of said modification, the rollback being partly shown in 90 section;

Fig. 7 is a horizontal section showing another alternative form of the invention;

Fig. 8 is a detail perspective view of the expanding member shown in Fig. 7, and 95

Fig. 9 is a detail plan view of the expandable shaft end shown in Fig. 5 illustrating the normal condition thereof.

The latch construction which I have partially illustrated in the accompanying drawings constitutes no essential feature of the present invention, and it will be clearly understood as this description proceeds that the subject matter of this application is capable of adaptation and use in connection 100 with many different types of door latches now known in the art and the essential features thereof are also applicable to other

analogous uses. In all cases where means for quickly effecting in a positive manner a rigid locking connection between two cooperating parts and which, when necessary, will enable the separation of said parts to be readily effected, may be found of material advantage, the invention to be presently described is easily adapted. However, since the device is particularly designed for the purpose of effecting a quick and reliable operating connection between the handle shaft and the rollback of a door latch such as is used on automobile doors, I have selected this application of the invention for illustrative purposes. Accordingly, in the accompanying drawings, a portion of an automobile door 5 is shown. The inner face of this door is mortised in the usual manner to receive the latch casing 6 within which the latch bolt and the projecting and retracting mechanism therefor are mounted. The latch bolt retracting means includes the customary rollback 7 which is journalled for oscillating or rocking movement at its ends in spaced parts of the latch case 6. This rollback may be of any desired form requisite to insure its proper cooperation with a part of the latch bolt whereby the bolt is retracted when said rollback is oscillated in one direction. In every case however, the rollback 7 is provided with a bore 8 coincident with its axis of oscillation, said bore being of any desired cross sectional shape. In the several illustrated forms of my invention, I have shown the bore through the rollback as of rectangular form. Preferably, the opposite ends of the rollback 7 are flush with the outer surfaces of the inner and outer walls respectively of the case 6.

40 The door structure 5 has a transversely extending handle shaft receiving opening 9 bored therethrough substantially in line with the rollback 7 and in the outer end of this opening a suitable handle shaft bearing 10 is secured, said bearing however, constituting no essential feature of the present improvements.

45 The handle shaft includes a cylindrical portion 11 supported in the bearing 10 and a reduced portion 12 of the same cross sectional form as the bore 8 of the rollback 7. The end of this reduced portion 12 of the handle shaft is longitudinally split centrally thereof as at 13, the length of said split somewhat exceeding the length of the rollback bore. Thus, there is provided upon said end of the handle shaft the two separable or laterally expandible portions 14. The inherent resiliency of the metal maintains a normal close contacting relation between the inner opposed faces of these shaft portions. The said opposed faces at the extremity of the shaft are, however, chamfered or beveled as indicated at 15 to extend in divergent relation to each other. This split

end of the shaft is so formed relative to the inner portion of the shaft section 12 that the outer side faces 16 of the portions 13 extend longitudinally in slightly convergent relation towards the inner faces thereof in 70 the normal condition of said shaft end. From these outer faces 16 at the extremity of each shaft portion 14 lips 17 laterally project. These lips however, do not normally project beyond the extended planes of 75 the opposite side faces of the inner part of the shaft section 12. Thus, as indicated in Fig. 2 of the drawings, they may readily pass through the bore of the rollback.

At the inner end of the bore 8 of the rollback, opposite side walls thereof are provided with shallow recesses or seats 18, the purpose of which will be hereinafter explained. Through the hub extension 19 on this inner end of the rollback which is 80 mounted in the casing wall or plate, the cylindrical openings 20 are drilled, said openings being in diametrically opposed relation and communicating with the end of the rollback bore substantially midway between the recesses or seats 18.

Two expanding elements 21 each of which is of substantially triangular cross sectional form, are detachably connected with the inner end of the rollback. For this purpose, I provide each of the expanding elements with a cylindrical longitudinally extending stud 22 at one of its ends which is adapted to be frictionally fitted in the inner end of one of the openings 20. Thus, the triangular shaped expanding members are retained in spaced relation to each other within the inner end of the rollback bore. When so applied, one of the side faces of each of said members is positioned in a plane parallel with the end face of the rollback and is provided with a suitably formed socket 23 therein. These sockets are adapted to receive suitable pins or studs on the ends of crossed pivotally connected levers indicated at 24 in Fig. 4 of the drawings for the purpose of removing said expanding members and detaching the same from the rollback when it becomes necessary to remove the handle shaft, as for instance in repainting the door. These levers can be easily inserted between the edge of the upholstery on the inner face of the door indicated at 25 and the wall of the latch case so that it becomes unnecessary to detach or remove the upholstery in order to disconnect the shaft end from the rollback.

From the above description of this embodiment of my invention, it will be seen that the changes required in the rollback construction are of a very simple character and the rollback may be readily provided with the two expanding members 21 by the latch manufacturer without materially increasing the manufacturing cost or the sell-

ing price of the latch to the automobile manufacturer. The latter may readily procure the handle shafts of the construction above described, and after the latch has been applied to the inner face of the door, it is then only necessary to insert the handle shaft from the outer side of the door through the opening 9 and into the bore 8 of the rollback. As the split end of the shaft 13 is inserted through the rollback bore and approaches the expanding members 21, the apex edges of these members engage between the divergent faces 15 on the shaft portions 14 and co-acting with opposite side faces of said expanding member, as axial pressure is applied against the shaft, said shaft portions 14 are expanded or spread laterally in opposite directions until the lips 17 snap into the seats or recesses 18 and the side faces 16 of said shaft portions are urged into binding frictional contact against the opposite side walls of the bore 8 of the rollback. In this manner, there is automatically produced a rigid locking connection between the shaft end and the rollback which effectively prevents turning or rotative movement of the shaft end in the rollback bore or the axial displacement of said shaft end in either direction relative to the rollback. Thus, the members 21 resist any externally applied pressure against the handle tending to force the shaft inwardly through the rollback while the lips 17 engaging the shoulders formed by recesses 18 effectively prevent axial movement of the shaft in the opposite direction and its detachment from the rollback by an outward pull exerted on the handle. All lost motion between the handle shaft and the rollback in the actuation of the lock is thus obviated and any metallic noise incident to looseness of the shaft end in the rollback bore is precluded. In other words, the two parts operate substantially as a single unit.

In Fig. 5 of the drawings, I have shown another embodiment of the invention wherein the expanding member 21' is in the form of a single metal rod or bar of triangular cross sectional form extending diametrically across the end of the rollback bore and having its ends engaged in similarly shaped openings 20' formed through the inner end hub of the rollback. In order to permit of the detachment or removal of this expanding member, in this construction, the inner end of the rollback is journaled in a separate plate 26 detachably secured to the inner wall of the latch case by the screws 27. It would, of course, first be necessary to partly detach the upholstery 25 to remove the plate 26 so that the expanding member 21' could be driven out by means of a suitable punch.

In this embodiment of the invention, the split end of the shaft is normally in the condition shown in Fig. 9 of the drawings, the inner opposed faces of the shaft portions 14' extending in spaced divergent relation to each other from the inner end of the split. The extremities of these shaft portions have a slight lateral angular offset as indicated at 28 so that the outer side faces thereof are obliquely inclined in an outward direction. The inner sides of these angular extremities of the shaft portions are provided with inwardly projecting lips 29 which limit the inward movement of the shaft portions 14' towards each other, said lips having inclined or beveled end faces adapted to ride against the divergent side faces of the expanding member 21'.

The opposite side walls of the rollback bore at their inner ends are outwardly inclined or beveled as indicated at 30. Thus, it will be understood that when the shaft end is inserted into the bore of the rollback, the lips 29 coating with the divergent side faces of the member 21' spread or expand the shaft portions 14' laterally so that the side faces thereof are caused to tightly bind against the opposite side walls of the bore and said shaft portions at their extremities are also engaged against the inclined faces 30 of the rollback bore, while the lips 29 spring behind the member 21', thereby locking the shaft end against outward axial movement in said bore. The angularly offset extremities 28 of the two portions 14' of the shaft are properly tempered so as to permit of the slight relative resiliency therein with respect to the remaining portions of the shaft parts 14' whereby the lips 29 may lock over the rear face of the member 21' without releasing the frictional binding pressure of said shaft parts against the walls of the bore.

In Figs. 7 and 8 of the drawing, I have shown another alternative of the device, wherein the split end of the shaft is substantially of the same form as last described with the exception that the extremities thereof are not laterally offset, and instead of providing the solid metal expanding member 21', I provide the expanding member 21^a of heavy gauge sheet metal. This metal sheet is bent into triangular shaped form with the longitudinal edges 2^a thereof normally spaced apart. The ends of this member are adapted to be engaged in triangular shaped openings in the inner end of the rollback as in the construction last described. It will therefore, be apparent that when the split end of the shaft is inserted through the bore of the rollback, the lips 29^a on the extremities of the expandable portion of the shaft will cooperate with the divergent walls of the member 21^a and as the frictional binding pressure of the outer faces of said shaft portions against the walls of the rollback approaches the maximum, said divergent walls of the member 21^a will yield suffi-

ciently so that the lips 29^a will engage behind the inturned flanges at the rear edges of said walls as shown in Fig. 7, thereby locking the parts of the shaft end in expanded relation with each other. In this construction also, it is of course necessary to provide the separate bearing plate 26 for the inner end of the rollback to permit of the withdrawal of the expanding member 21^a without necessitating the complete removal of the latch.

From the foregoing description considered in connection with the accompanying drawings, the several illustrated embodiments of the device will be clearly understood. It will be seen that I have provided means for automatically effecting a rigidly locked connection between the end of the operating shaft and the rollback, thereby eliminating the additional step or operation of inserting a screw, wedge or other element for the purpose of expanding the split end of the shaft after it has been inserted through the rollback bore. Thus, the equipment of the door latches by the automobile manufacturer with the operating handles therefor will be appreciably expedited by means of my present invention. I have referred to several different forms of the shaft end expanding means and means for mounting or arranging the same in detachable fixed relation to the inner end of the rollback. However, in these particulars various other mechanical means might be devised for accomplishing the same purpose, and as I believe it to be new in this art to provide such means in fixed relation to the rollback which coacts with the shaft end to automatically produce a rigid locking connection with the rollback in the act of inserting the shaft in the bore thereof, I do not desire to be limited to the particular mechanical forms which I have herein referred to. Accordingly, it is to be understood that in practice I reserve the privilege of resorting to all such legitimate changes in the form, construction and relative arrangement of the various parts as may be fairly embodied within the spirit and scope of the invention as claimed.

I claim:

1. In combination with a door latch provided with a rollback having a shaft receiving bore, an operating shaft adapted to be inserted in said bore, and means cooperating with the shaft end and automatically acting in the insertion of said shaft end into the bore to lock the shaft in said bore against rotative or axial movement relative to the rollback.

2. In combination with a door latch provided with a rollback having a shaft receiving bore, an operating shaft adapted to be inserted in said bore, and means mounted at one end of the rollback bore in fixed

relation thereto and automatically cooperating with the shaft end as the latter is inserted into said bore to rigidly lock the shaft end in said bore against rotative or axial movement relative to the rollback.

3. In combination with a door latch provided with a rollback having a shaft receiving bore, an operating shaft adapted to be inserted in said bore, and means detachably connected with one end of the rollback in fixed relation thereto and extending diametrically of the rollback bore adapted to automatically coact with the shaft end as the latter is inserted into said bore to rigidly lock the shaft end in the bore against rotative or axial movement relative to said rollback.

4. In combination with a latch secured to the inner side of a door and provided with a rollback having a shaft receiving bore, an operating shaft, and means mounted in fixed relation to the rollback at the inner end of its bore adapted to automatically cooperate with the shaft end as the latter is inserted into said bore and rigidly lock said shaft end therein with its end face substantially flush with the inner end face of the rollback.

5. In combination with a latch secured to the inner side of a door and provided with a rollback having a shaft receiving bore, an expanding member secured in fixed relation to the inner end of the rollback and extending into the rollback bore, and an operating shaft having a longitudinally split end insertable into said rollback bore, and said expanding member adapted to automatically cooperate with said split end of the shaft and expand the same into frictional binding engagement with the walls of said bore to prevent relative rotation between said shaft and the rollback.

6. In combination with a latch secured to the inner side of a door provided with a rollback having a shaft receiving bore, an expanding member, the inner end of said rollback having a part provided with means for the detachable connection of the expanding member with said part and said member projecting into the bore of the rollback, and an operating shaft having a split end for insertion in said bore and said member adapted to engage in the split of said shaft end in the insertion thereof to automatically expand said shaft end into binding engagement with opposite walls of the bore and thereby prevent relative rotation between the shaft and the rollback.

7. In combination with a latch secured to the inner side of a door provided with a rollback having a shaft receiving bore, an expanding member, the inner end of said rollback having means for the detachable connection of the expanding member therewith and said member projecting into the bore of the rollback, and an operating shaft

- having a split end for insertion in said bore and said member adapted to engage in the split of said shaft end in the insertion thereof to automatically expand said shaft end into binding engagement with opposite walls of the bore and thereby prevent relative rotation between the shaft and the rollback, said member also preventing axial movement of the shaft end through said bore in one direction, and the split parts of said shaft end being provided with means coacting with the rollback to prevent axial movement of the shaft end in the opposite direction.
8. In combination with a latch secured to the inner side of a door and provided with a rollback having a shaft receiving bore, the inner end of said rollback having opposed diametrically extending openings therein, expanding members having parts detachably engaged in the respective openings and projecting into said bore, said expanding members being of triangular form in cross section, and an operating shaft having a split end portion adapted for insertion in said bore, the inner faces of said split portions of the shaft end at their extremities being divergently beveled and adapted to coact with said expanding members in the insertion of said shaft end to thereby expand said split portion of the shaft end into frictional binding engagement with opposite walls of said bore and prevent relative rotation between the shaft and the rollback.
9. In combination with a member having a bore, a shaft having a longitudinal split end portion adapted for insertion in said bore, and means mounted in fixed relation to one end of said bore adapted to coact with said split end of the shaft upon the insertion thereof to expand the same into frictional binding engagement with the walls of the bore, and said shaft end having means co-operating with said expanding means and said member when the shaft end is expanded to thereby lock the shaft against axial move-
- ment in either direction relative to said member.
10. In combination with a door latch provided with a rollback having a shaft receiving bore, an operating shaft adapted to be inserted in said bore, and means for detachably securing the shaft to said rollback, including a non-rotatable locking member secured in fixed relation to the rollback and having a part projecting radially into the bore at one end thereof, and said part of the locking member yieldable co-acting with means on said shaft to lock the shaft upon insertion of the latter in said bore against axial movement in one direction relative to the rollback.
11. In combination with a door latch provided with a rollback having a shaft receiving bore, an operating shaft adapted to be inserted in said bore, and means for detachably securing the shaft to said rollback, including a locking member carried by the rollback and projecting radially into the bore at one end and at one side thereof, and said member and the shaft end having yieldable co-acting parts to lock the shaft in said bore against axial movement in one direction relative to the rollback.
12. In combination with a door latch provided with a rollback having a shaft receiving bore, an operating shaft adapted to be inserted in said bore, and means for detachably securing the shaft to said rollback including a locking member having a fixed connection at one of its ends to the rollback, and the other end of said member extending inwardly at one side of said bore and adjacent to one end of the rollback, and said latter end of the locking member and the end of the shaft being provided with relatively yieldable co-acting means to lock the shaft in said bore against axial movement in one direction relative to the rollback.
- In testimony that I claim the foregoing as my invention, I have signed my name hereto.
- MORTIMER C. LYDDANE.
